UNITED STATES PATENT OFFICE.

THOMAS MALCOLM MANSON, OF TORONTO, ONTARIO, CANADA, ASSIGNOR TO CLEAR VISION PUMP COMPANY, LIMITED, OF TORONTO, CANADA.

GASOLINE-DISPENSING DEVICE.

Application filed December 9, 1924. Serial No. 754,868.

The principal objects of the invention are to provide means for automatically draining the dispensing bowl upon the closing of the door but which may be rendered temporarily inoperative if it is desired to operate the dispenser with the door closed or if it is desired to lock the device for a short period without draining the bowl.

A further and important object is to devise a structure which will prevent the operator from manipulating the drain valve while dispensing and thereby cheating the customer.

The principal feature of the invention consists in the arrangement of a removable member between the drain valve of the measuring bowl and a door in the casing whereby the drain valve will be operated automatically on the closing of the door or said door may be closed without draining the bowl by manipulating the said removable member.

A further feature consists of the provision of a guard to cover the drain valve spindle to prevent unwarranted operation thereof.

In the drawings, Figure 1 is a perspective view of a dispensing device to which this invention is applied.

Figure 2 is a part sectional view of a dispensing device showing the improved drain valve arrangement in side elevation and the door frame in longitudinal section.

Figure 3 is a perspective view of the drain valve and the co-operating parts inside of the casing.

Figure 4 is a view similar to Figure 3, showing the means for operating the valve moved out of operating position to enable the door to be locked without draining the bowl.

Figure 5 is a full size sectional view of the drain valve.

In the construction of dispensing device herein shown, the measuring bowl 1 is supported at the top of a tapering column 2 which has a door opening in the side thereof to which is secured the frame 3. This frame is formed with a semi-circular pocket extension 4 at the bottom and centrally of the pocket extension are arranged the oppositely disposed slots 5 which are closed by the wall of the casing.

A door 6 adapted to close the opening in the frame is provided with a pair of arms 7, the outer ends of which are joined by a

cross bar 8 which extends through the slots 5 of the pocket extension 4 and upon this cross bar is arranged a lug 9 which swings in the semi-circular recess 10 within the pocket structure 4.

The dispensing pipe 11 leading downwardly from the bowl is provided with a T 12, the side branch of which leads to the dispensing tube connection 13.

A pipe 16 extends downwardly from the T 12 and connects with the overflow pipe 17 from the measuring bowl which leads to the main supply tank.

A valve 14 is arranged in the pipe 16 immediately below the T 12 and is provided with a spring held valve member 15 closing the passage through the pipe 16.

The valve 15 is provided with a spindle 18 which is arranged in horizontal alignment with the upper portion of the recess 10 in the door frame structure.

An arm 19 is pivotally mounted on the pipe 16 immediately below the valve and extends outwardly and upwardly past the end of the valve spindle and has a horizontally arranged bushing 20 at its upper end adapted to move into axial alignment with the spindle and within this bushing is slidably mounted a stem 21 which extends into the recess 10 of the door frame.

When the stem 21 is arranged in alignment with and abuts the end of the spindle 18, the lug 9 on the cross bar 8 of the door will engage the end of the spindle and push inwardly thereon upon the closing of the door, so that when the dispenser is to be locked up over night, or for any lengthy period, the valve 14 will be opened to allow the gasoline to drain out of the measuring bowl. The lug 9 will not engage the stem 21 when it is moved laterally sufficiently far to miss the end of the valve stem 18.

A forked arm 22 is pivotally mounted on a pin 23 at the inner side of the column 2 below the door frame and the fork extends to either side of the stem 21.

A knob 24 secured to the lower end of the arm extends through a slot in the column so that the arm may be swung from the outside. A spring 25 holds the arm with the knob 24 engaging one end of the slot and so that the stem 21 is normally maintained in alignment with the spindle 18 of the valve. This pivotal arm provides a means for swinging the stem 21 which is carried on the pivotal

arm 19 to one side so that the outer end will not be engaged by the lug 9 of the door as indicated in Figure 4 of the drawings showing the door shut and the spindle 21 extending past the edge of the lug 9.

This provision is made so that the door may be closed in stormy weather, or if the dispenser is being left merely for a short time or if for any reason it is desired to 10 operate with the door closed.

The arm 19 is provided at its upper end with a semi-cylindrical hood 26 which extends over the valve stem in such a manner that the free movement of the arm will not 15 be interfered with but the hood covers the valve spindle 18 and operating stem 21 to prevent the manipulation of the drain valve by the operator of the dispenser. The cheating of the customer is thus made impossible.

It will be seen that as the operating stem 21 is held normally in a position to be engaged by the lug 9 upon the closing of the door the drain valve will be operated when 25 the dispenser is locked up for the night whereas the simple action of opening the door closes the valve and allows the filling of the bowl.

The dispensing tube is always full of gasoline and normally hangs upon a hook arm which automatically controls the filling of the bowl, details of this mechanism being fully disclosed in my pending application filed in the United States under date of December 9, 1924, Serial No. 754,866. When 30 the dispenser is to be locked up the valve 27 is lifted off the hook and the operating lever 27' of the valve is placed inside of the standard.

40 The door frame 3 is formed with two notches 28 and 29, one to receive the valve stem 28' and the other the valve operating link 29' and when these members are inserted into the notches the door is then closed, thus 45 locking the valve operating lever 27' within the standard in such a manner that the valve cannot be tampered with or operated.

The device is extremely simple and there is nothing of a delicate nature to get out of order.

50 What I claim as my invention is:—

1. In a gasoline dispensing device, the combination with the measuring bowl having fill and drain pipes connected therewith, a 55 casing enclosing said pipes having a door therein, and a spindle actuated drain valve in said drain pipe for emptying the gasoline from the measuring bowl, of a bodily displaceable valve operating member mounted 60 adjacent the drain valve spindle, means for displacing said valve operating spindle to move the same into or out of operative alignment with the drain valve spindle, and an operating member connected with said door 65 and actuated thereby on the closing of the

door to engage and operate said movable member when the latter is in its operatively aligned position.

2. In a gasoline dispensing device, an upright casing having a door opening therein 70 and a frame surrounding said opening, said frame having a pocket below the door opening communicating with the interior of the casing, a door hinged on said frame and having a bar extending through said pocket and 75 forming the hinge pintle for the door, a measuring bowl mounted above said casing, a spindle-operated drain valve arranged in said casing and connected with said bowl, a 80 slidable member normally supported in operative alignment with the valve spindle, a lug on said bar within the pocket in alignment with the valve spindle for engaging and sliding said slidable member inwardly upon the closing of the door, and means for moving said slidable member out of its normal 85 operative position.

3. In a gasoline dispensing device, an upright casing, a dispensing bowl mounted on 90 said casing, a drain pipe from the dispensing bowl, a spring closed drain valve in said pipe having an operating spindle projecting therefrom, an arm pivotally mounted on the drain pipe and having a guard at one end 95 extending over the valve operating spindle, a stem slidably mounted on said arm below the guard in alignment with the spindle, a door opening in said casing, a door closing said opening, a member carried by said door in alignment with said slidable stem for engaging the same, and means for swinging said pivoted arm to move the stem out of alignment with the engaging member carried by the door.

4. In a gasoline dispensing device, the 105 combination with a casing, a measuring bowl mounted on said casing, a conduit leading from the bottom of said bowl through said casing, a drain valve arranged in said conduit and enclosed by said casing, an opening in said casing adjacent said valve, and means for closing said opening to prevent 110 access to said valve, of displaceable valve-operating means disposed between said drain valve and said closing means, means connected with said closing means to open said valve for actuating said valve-operating means, and means independent of said actuating means for displacing said valve-operating means to render the same said valve-operating means temporarily inoperative by 115 said actuating means.

5. A gasoline dispensing device, comprising a casing having a door opening therein, a door frame having an extension on the bottom formed with a recess opening inwardly and a transverse opening intersecting the recess, a door having a hinge bar pivotally supported in said transverse opening and extending across said recess, said bar having 120

- a lug thereon adapted to swing in said recess, a dispensing bowl arranged at the top of said casing, a drain pipe leading from the dispensing bowl, a spring closed valve in said 5 drain pipe having an operating spindle, an arm pivotally mounted on said drain pipe, a slidable stem carried by said arm in alignment with said valve spindle, means for normally holding said slidable stem in its 10 aligned position to be engaged by said hinge lug, said holding means being movable to shift the stem out of engagement with the hinge lug.
6. In a gasoline dispensing device, the 15 combination with the measuring bowl, fill and drain pipes connected therewith, a casing enclosing said pipes having a door
- therein, and a spring-closed drain valve in said drain pipe having an operative spindle projecting horizontally therefrom, of an 20 arm pivotally mounted to swing on a vertical pivot, a horizontally disposed stem 25 slidably mounted on said arm on a level with said valve-operating spindle and adapted by swinging said arm on its pivot to be carried by said arm into and out of alignment with the valve spindle, a contact member on the door in alignment with the valve spindle for engaging said stem to move same inwardly 30 when the latter is in alignment with the valve spindle, and means for swinging said arm on its pivot.

THOMAS MALCOLM MANSON.
